UNITED STATES PATENT OFFICE.

ALBERT F. LAUDENSACK, OF NEW HAVEN, CONNECTICUT, ASSIGNOR TO WINCHESTER REPEATING ARMS CO., OF NEW HAVEN, CONNECTICUT, A CORPORATION.

CHARGING DEVICE FOR TUBULAR-MAGAZINE GUNS.

No. 910,397.

Specification of Letters Patent.

Patented Jan. 19, 1909.

Application filed June 18, 1908. Serial No. 439,193.

To all whom it may concern:

Be it known that I, ALBERT F. LAUDENSACK, a citizen of the United States, residing at New Haven, in the county of New Haven and State of Connecticut, have invented a new and useful Improvement in Charging Devices for Tubular-Magazine Guns; and I do hereby declare the following, when taken in connection with the accompanying drawings, and the letters of reference marked thereon, to be a full, clear, and exact description of the same, and which said drawings constitute part of this specification, and represent, in—

15 Figure 1 a view partly in section and partly in side elevation of a charging device constructed in accordance with my invention and shown as applied to a tubular cartridge magazine for charging the same, the magazine being shown in longitudinal section. Fig. 2 a view in side elevation of the cartridge-retaining spring, the lower end of the tube being indicated by broken lines. Fig. 3 a broken plan view of the lower half of the 25 device. Fig. 4 a broken view in longitudinal section of the lower end of the device showing the cartridge-retaining spring functioning to prevent the escape of the cartridges. Fig. 5 a plan view of the entire device shown 30 on a reduced scale.

My invention relates to an improved charging device for introducing cartridges into the magazines of rifles, the object being to provide for this purpose a simple and convenient 35 device enabling a person to introduce a predetermined number of cartridges, and designed with particular reference to use in shooting galleries.

With these ends in view my invention consists in a device having certain details of construction as will be hereinafter described and pointed out in the claims.

In carrying out my invention as herein shown, I employ a small tube 2 having its upper end 3 closed or partially closed and its lower end open and cut away on one side to form a clearance slot 4 which gives additional freedom for the escape of the cartridges from the open lower end of the tube 45 when the same is tilted into an inclined position as shown in Fig. 1, and which also permits the entrance into the passage of the tube of the inwardly bent lower end 5 of a cartridge-retaining spring 6 the upper end of

which is formed with lateral arms 7 bent to 55 clasp the tube 2 so as to hold the spring in place thereon. The bent portion 5 of the spring is struck inward to form a cartridge-stop 8 which is engaged by the heads of the cartridges and prevents them from escaping 60 from the lower end of the tube 2 except when the stop 8 is cleared from their path. For the latter purpose I form at the lower end of the spring what I shall call, in default of a better term, a segmental "operating-shoe" 9 standing at a right angle to the axis of the spring and curved by preference to conform to the curvature of the tubular cartridge magazine 10 of the rifle with which the charger is to be used, as will be more fully described later on. 70

To provide for the introduction into the magazine 10 of a predetermined number of cartridges *en bloc* or without counting them individually, I form the exposed upper face of the tube with one or more finger-holes 11 75 made large enough to permit a sufficient entrance of the finger or thumb into the passage of the tube to engage with and control the cartridges therein. As shown the tube has two of these finger-holes 11, and 80 two will probably be all that will be required, though their number is immaterial. These finger-holes are very carefully spaced in location with respect to the lower end of the tube and the length of the cartridges to be 85 counted. Thus the first hole 11 from the lower end of the tube may be spaced so that five cartridges will be contained within that portion of the tube lying between the cartridge-stop 8 and the middle of the hole. In 90 the same manner the upper of the two holes will be spaced with reference to the lower end of the tube so that ten cartridges will be contained between it and the cartridge-stop 8. In this way the cartridges contained in it will 95 be counted *en bloc*, as it were, rather than individually. By tipping the tube the cartridges contained in it will gravitate to its lower end in which they will be arrested by the cartridge-stop 8. Now if 100 the finger is applied to the lower finger-hole 11 it will act as a stop to prevent any of the cartridges above the hole from escaping from the tube when the same is applied to the magazine of the gun and pressure placed upon the spring 6 so as to clear the stop 8 from the lower end of the tube. In the same way if 105 the finger or thumb is applied to the upper

hole 11 the ten cartridges located between the hole and the projection 8 will be cut off, so to speak, from the cartridges above the hole.

5. The use of the device is illustrated in Fig. 1 in which the lower end of the tube 2 is shown as inserted into a tubular magazine 10 having a feeding-opening 12 so that the operating-shoe 9 rides upon the magazine at 10 a point just below the opening 12. By the exertion of a little pressure the spring 6 is caused to yield so as to clear the stop 8 from the lower end of the tube from which a given number of cartridges will now run into the 15 magazine according to the finger - hole "stopped."

It will be apparent that if the device is gradually drawn away from a magazine which has been filled, the spring 6 will 20 cover its cartridge-retaining position and prevent any cartridges from being spilled.

I claim:

1. In a charging device for tubular magazine guns, the combination with a tube 25 formed with one or more finger-holes spaced with reference to the open lower end of the tube and the length of the cartridges to be charged, of a cartridge-retaining spring applied to the lower end of the said tube.
- 30 2. In a charging device for tubular magazine guns, the combination with a tube formed with one or more finger-holes spaced with reference to the open lower end of the

tubes and the length of the cartridges to be charged, of a cartridge-retaining spring applied to the lower end of the tube and formed at its lower end with a transversely arranged operating-shoe for engagement with the gun so as to release the cartridges in the tube.

3. In a charging device for tubular magazine guns, the combination with a tube formed with one or more finger-holes spaced with reference to the open lower end of the tube and the length of the cartridges to be charged, of a cartridge-retaining spring applied to the lower end of the tube and formed at its lower end with an inwardly projecting cartridge-stop and an operating-shoe.

4. In a charging device for tubular magazine guns, the combination with a tube 50 formed with one or more finger-holes spaced with respect to the lower end of the tube and the length of the cartridges, and the tube being formed at its lower end with a clearance slot; of a cartridge-retaining spring applied to the tube, having its lower end bent inwardly to enter the said slot and formed with an operating-shoe.

In testimony whereof, I have signed this specification in the presence of two subscribing witnesses.

ALBERT F. LAUDENSACK.
